(57) **CLAIM**

The ornamental design of a portable DVD player with rotatable screen, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a portable DVD player with rotatable screen according to an embodiment of my new design (in closed position with inwardly projecting screen);

FIG. 2 is a top plan view thereof;

FIG. 3 is a front elevation view thereof;

FIG. 4 is a right side elevation view thereof;

FIG. 5 is a left side elevation view thereof;

FIG. 6 is a back elevation view thereof;

FIG. 7 is a bottom plan view thereof;

FIG. 8 is a perspective view thereof (in open position with non-rotated screen);

FIG. 9 is a perspective view thereof (in open position with rotated screen);

FIG. 10 is a perspective view thereof (in closed position with outwardly projecting screen);

FIG. 11 is a perspective view of a portable DVD player with rotatable screen according to another embodiment of my new design (in closed position with inwardly projecting screen);

FIG. 12 is a top plan view thereof;

FIG. 13 is a front elevation view thereof;

FIG. 14 is a right side elevation view thereof;

FIG. 15 is a left side elevation view thereof;

FIG. 16 is a back elevation view thereof;

FIG. 17 is a bottom plan view thereof;

FIG. 18 is a perspective view thereof (in open position with non-rotated screen);

FIG. 19 is a perspective view thereof (in open position with rotated screen); and,

FIG. 20 is a perspective view thereof (in closed position with outwardly projecting screen);

Portions in broken lines are for illustrative purposes only and form no part of the claimed design.
